UNITED STATES PATENT OFFICE.

MARION EUGENE ROZELLE, OF CHAMBERSBURG, PENNSYLVANIA.

GRINDING-MILL.

1,034,034.

Specification of Letters Patent. Patented July 30, 1912.

Application filed April 3, 1909, Serial No. 487,711. Renewed December 15, 1911. Serial No. 666,039.

To all whom it may concern:

Be it known that I, MARION E. ROZELLE, a citizen of the United States, residing at Chambersburg, in the county of Franklin 5 and State of Pennsylvania, have invented a certain new and useful Improvement in Grinding-Mills; and I do hereby declare the following to be a full, clear, and exact description of the invention, such as will enable others skilled in the art to which it 10 appertains to make and use the same.

This invention relates to grinding mills and more especially to mills of this kind intended for use in roller flour mills, the 15 improved mill being particularly adapted for grinding pure middlings, fine flat middlings, flat tailings, and low grade stock.

The invention aims to provide a grinding mill in which the grinding roll and the 20 cylinder in which it is arranged coact with each other in an improved manner in order to produce a rapid and thorough grinding of the stock, and to furnish a construction in which the grinding ring has an improved 25 arrangement with respect to the cylinder and roll. This grinding ring normally surrounds and bears against the discharge end of the roll, and the material, after being ground by flutes on the roll and cylinder, is 30 still more finely divided by passing between the grinding ring and the portion of the roll against which it bears. Improved means are also provided for adjusting the 35 grinding ring in order to move it into more or less close contact with the coacting surface of the roll, and such means preferably embody a single manually operated mechanism operable from the exterior of the casting.

Another important feature of the invention is that the grinding ring is automatically moved out of co-operation with the grinding roll when an excessive amount of material enters the mill and overloads or 45 chokes the latter. To this end the grinding ring is yieldingly held against the discharge end of the grinding roll, and when an excess of material passes between the grinding roll and cylinder the ring will be 50 moved axially away from the roll and toward the discharge end of the mill, thus relieving the machine.

A still further object in view is to provide a mill of this kind in which one of the shaft- 55 bearings is adjustable so that if the grinding ring when adjusted axially to the de-

sired extent with respect to the grinding roll is out of center with respect to said roll, centering can be effected by adjusting the shaft-bearing to the proper position. 60

In the accompanying drawing:—Figure 1 is a vertical longitudinal section through a grinding mill constructed in accordance with the invention, Fig. 2 is an elevation, partly in section, of the discharge end of 65 the mill, and Fig. 3 is a vertical transverse section on line 3—3 of Fig. 1.

The casing A of the mill is preferably formed in three sections; an intermediate supporting section 4, which carries the 70 grinding cylinder; an end section 5, provided with a feed-spout 6 and a shaft bearing 7; and an end section 8 provided with a discharge opening 9 and a shaft bearing 10. The grinding roll B is mounted upon 75 a shaft 11 journaled in the bearings 7, 10, and said roll carries at its receiving end a feed-worm 12 which receives the material fed through the spout or hopper 6, and forces it longitudinally of the machine between the cooperating grinding surfaces of 80 the grinding roll and cylinder, such material after passing beyond the grinding roll then being discharged from the mill through the opening 9. 85

The grinding cylinder, which is formed by a portion of the intermediate section 4, is substantially frusto-conical in form. Said cylinder, denoted in the drawing by reference character 4^a, extends at one end in 90 substantially horizontal direction beyond an upright flange 4^b of the section 4, and this end portion, denoted by reference character 4^c, is surrounded by an annular space 4^d, as shown in Fig. 1. 95

Throughout the length of its grinding surface the cylinder 4^a is provided with a series of flutes or corrugations 13, as shown in Figs. 1 and 3. Although these flutes or corrugations are illustrated as spirally arranged, they may be straight in certain cases, and the semi-circular form of the flutes, as illustrated, may also be departed from in certain cases. These flutes coact with similarly arranged flutes 14 on the 105 frusto-conical portion B^x of the grinding roll, which portion fits within the cylinder 4^a with a certain amount of clearance, as shown in Fig. 3. The flutes 14 on the grinding roll are of substantially the same form 110 as the flutes 13, and are adapted to be placed in alignment therewith by the rotation of

said roll. The flutes 14 do not extend completely to the discharge end of the grinding roll but merge into a smooth tapered portion 15 formed integral with the roll.

5 Coating with the smooth end portion 15 of the grinding roll is a grinding ring 16 having a hard grinding surface of tapering form afforded in part by a tapering shoulder 17 entering the space between the end of the 10 grinding cylinder and the smooth portion of the roll and coating with a seat or groove 18 of annular form cut in the inner surface of the portion 4^c of the grinding cylinder. The ring 16 is mounted on a worm gear 19 threaded on the portion 4^c of the cylinder within the annular space 4^d, as shown at 20, so that when said worm gear is rotated it will be moved laterally along the cylinder and axially of the grinding roll. This movement of the worm gear is effected by means of a worm 21 located within the casing section 8 transversely of the latter and operated by means of a hand wheel 22. The connection between the grinding ring 16 and worm gear 19 is a yielding one so that the grinding ring may yield longitudinally of the machine and be forced out of the angle between the cylinder and grinding roll by an excess of material. In the embodiment shown, said 25 connection comprises screw bolts 23 passing freely through openings in the grinding ring and threaded into the worm gear 19, as shown in Fig. 1, and interposed between the grinding ring and the heads of said screw 30 bolts are helical springs 24.

The bearing 10 of the shaft 11 is carried by a casting 25 having an end plate 26 by which it is bolted to the casing section 8 by means of screw bolts 27. The openings 28 in 40 the end plate 26 through which the screw bolts pass are of somewhat greater diameter than the screw bolts, so that adjustment of the casting 25 in any direction with respect to the casing may take place. In this way 45 the shaft, which passes through the end opening of the casing with clearance in all directions, may be adjusted to center the grinding roll in the grinding ring.

In the operation of the machine the material which is fed between the grinding roll and cylinder is subjected to a very thorough comminuting action by the coöperating flutes 13, 14, which move alternately into and out of alignment with each other. The 50 material then passes between the smooth surface 15 of the grinding roll and the grinding ring and in this manner it is ground to a still greater degree of fineness, it then passing into the discharge section of the 55 casing and out of the discharge opening. Although the tapered end portion of the grinding roll and the inner surface of the grinding ring are smooth in the embodiment illustrated, the tapered end portion of 60 the grinding roll may be provided with cor-

rugations differing from the flutes on the main portion of the roll, and the grinding ring may be provided with similar corrugations; or the grinding ring may be corrugated and the tapered part of the roll smooth, as called for by the kind of stock 70 to be operated upon.

The adjustment of the grinding ring 16 with respect to the grinding roll, in order to make the contact more or less close, is 75 caused by the movement of the worm gear on its threads, the hand wheel 22 being turned in a proper direction for this purpose. Should the machine receive an excess of material, the same will force the grinding 80 ring away from the grinding roll as hereinbefore indicated, the grinding ring being guided in this movement by means of the screw bolts 23. When the charge is again reduced to normal the springs 24 will force 85 the grinding ring back into its initial or normal position, this position being regulated by the adjustment of the worm gear, as will be understood. When the grinding ring has been adjusted with respect to the grinding 90 roll it may be found that the latter is out of center with respect to the ring due to wear of the shaft in its bearings. If this is the case the bolts 27 are loosened and the bearing casting 25 may then be placed in such position with respect to the casing that the 95 grinding roll will be properly centered. When this has been done it is only necessary to tighten the screw bolt 27 again.

The ingress of the middlings or other material into the bearing casting 25 is prevented by means of a felt washer 29, surrounding the shaft and interposed between the casing section 8 and the end plate 26 of said bearing casting. 100

The springs 24 which urge the grinding ring toward the grinding roll may be adjusted in order to alter their tension, as required. This is done by means of their retaining nuts 24^x on the screw bolts 23, said 105 nuts adjustably holding in position the washers 24^y against which the ends of the springs are seated.

What I claim is:—

1. In a grinding mill, the combination of 115 a grinding cylinder, a frusto-conical grinding roll rotatable therein and having at its smaller end a smooth and tapered portion integral therewith, and a tapered grinding ring coating with said tapered portion of 120 the roll and adjustable longitudinally of the latter.

2. In a grinding mill, the combination of 125 a grinding cylinder, a grinding roll rotatable therein, a grinding ring surrounding the discharge end only of said roll, and a single manually operated mechanism to move said ring longitudinally of the roll.

3. In a grinding mill, a grinding cylinder, a frusto-conical grinding roll rotatable 130

therein and having at its smaller end a smooth and tapered portion integral therewith, a tapered grinding ring coacting with said tapered portion of the roll, and a geared connection to adjust said ring longitudinally of the roll.

4. In a grinding mill, the combination of a grinding cylinder, a grinding roll, and a grinding ring having a threaded connection 10 with the cylinder to move the ring axially and angularly with respect to the roll.

5. In a grinding mill, the combination of a grinding cylinder, a grinding roll, a member threaded on the cylinder wall to move lengthwise thereof, and a grinding ring carried by said member.

6. In a grinding mill, the combination with a grinding cylinder, of a worm gear threaded thereon to move lengthwise thereof, a grinding ring carried by said gear, and means to operate said gear.

means to operate said gear.

7. In a grinding mill, the combination of a casing which forms a portion of the grinding cylinder, an extension within the casing and which forms the end portion of the grinding cylinder, a worm gear threaded on said extension within the casing, a grinding ring carried by said gear, and means to operate said gear from the exterior of the casing.

30 casing. 8. In a grinding mill, the combination of a casing, a grinding roll rotatable therein, a grinding ring surrounding the end of said grinding roll, a member movable longitudinally within the casing by means of a threaded connection and supporting said grinding ring, and means to rotate said member from the exterior of the casing.

35

9. In a grinding mill, the combination
40 with a grinding roll, of a grinding ring sur-
rounding the roll, and means to hold said
ring yieldingly in contact with said roll and
to permit the former to move axially out of
such contact in the direction of the discharge
45 end of the mill.

10. In a grinding mill, the combination of a grinding cylinder, a grinding roll rotatable therein, a grinding ring coating with the grinding roll at the discharge end of the latter, and means to mount said ring so that it is axially movable away from the end of said roll and toward the discharge end of the mill by an excess of material.

11. In a grinding mill, the combination of a grinding cylinder, a grinding roll rota-

table therein, a grinding ring surrounding the discharge end only of said roll, and means to yieldingly hold said ring against the grinding roll and in the space between the latter and said cylinder, said means permitting the displacement of the ring axially away from the roll and toward the discharge end of the mill by an excess of material passing between the roll and cylinder. 60

12. In a grinding mill, the combination 65
of a grinding cylinder, a grinding roll rotatable
therin, a worm gear threaded on the
cylinder to move lengthwise thereof, means
to operate said gear, screw bolts carried by
said gear, a grinding ring guided on said
screw bolts, and springs on said bolts nor-
mally holding the grinding ring in contact
with the grinding roll. 70

13. In a grinding mill, the combination of a shaft, a grinding roll carried thereby, a casing in which said roll rotates and having an opening at one end through which the shaft passes with clearance in all directions, a grinding ring carried by said casing and coacting with said roll, an adjustable bearing for the shaft comprising a casting having an end plate, and bolts passing with clearance through openings in said end plate and into the casing at points located around the end opening therein. 85

14. In a grinding mill, the combination of a grinding cylinder, a grinding roll, a grinding ring surrounding the grinding roll at one end, a worm gear threaded on the cylinder to move lengthwise thereof, a yielding connection between said worm gear and said grinding ring, and means to rotate said worm gear. 90

15. In a grinding mill, the combination of a casing, a grinding roll rotatable therein, a member within the casing and having a threaded connection therewith by which said member is moved longitudinally of the casing, means to operate said member from the exterior of the casing, and a grinding ring yieldingly supported on said member and coacting with one end of the grinding roll. 95 100

In testimony whereof I affix my signature,
in presence of two witnesses.
